VALVED PLUMBING FITTING

Henry Gruen, New York, N. Y.

Application April 19, 1951, Serial No. 221,920

5 Claims. (Cl. 137—556)

1

This invention relates to plumbing fittings, and more particularly to a water supply fitting for a bath tub with valve means for diverting the water flow from such fitting to a shower fixture or attachment.

In such fittings as heretofore constructed, the water supply spout for the tub is provided with a device which may be manually operated to divert the water flow to a pipe leading to the shower attachment, and when the diverter is not in operation and the usual hot or cold water valves, or both, are open, the water passes freely through the tub spout and no water rises through the shower pipe, but after the said diverter is manually operated, the flow of water through the spout is interrupted and the water is caused to pass through said pipe to the shower attachment and the water pressure is adapted to hold the diverter in this position after the initial manual operation and as long as the supply pressure is maintained.

This arrangement has the disadvantage that the water cannot be conveniently diverted to the shower attachment until after a considerable amount of water has passed through the spout into the tub and an appreciable amount of water escapes through the spout to the tube even while the deflector is in operation, and moreover the closing of the usual valves automatically relieves the water pressure on the diverter device which must therefore be manually operated each time it is desired to deliver water to the shower attachment. These known devices have the further disadvantage that they are liable to cause objectionable noise and wastage of water.

One object of the present invention is to provide improved diverter means capable of being manually set at will in readiness to supply water to either the tub or the shower attachment. Another object is to provide a rotary diverter device that may effectively prevent any passage of water through the tub spout while the shower is in operation. Still another object is to provide a device which does not rely upon the water pressure to retain it in position for the supply of water to the shower, and which remains tightly in position even after appreciable wear of the contacting surfaces.

With these and other objects in view, the invention consists in the novel construction and arrangements of parts hereinafter described, illustrated in the accompanying drawings, and particularly pointed out in the appended claims, it being understood that various minor changes in the form and construction may be made without departing from the spirit of the invention or sacrificing any of the advantages thereof.

2

In the drawing Fig. 1 is a longitudinal section of a water spout with the diverter according to the invention embodied therein, Fig. 2 is a plan view of the spout, showing the external operating means for the diverter, and Fig. 3 is a cross-section on the line 3—3, Fig. 1.

Referring to the drawings, the spout 10 is internally screw threaded at its water inlet end 11 to receive an external screw thread on an enlarged end part 12 formed on an internal bushing 13 that fits into an enlarged bore portion 19 of the bore 20 of the spout, and the extremity of the bushing 13 at the inlet of the spout is internally screw threaded at 14 for the reception of the external screw thread on the end of the usual pipe supplying the hot and cold water to the spout.

The bushing 13 is formed with a downwardly tapered bore or socket for the reception of a similarly tapered plug 15 whose lower end is slightly spaced from the lower part of the said bore or socket, and a compression spring 21 is interposed between the upper part of the plug 15 and the surface of the said enlarged portion 19. The plug 15 has a passage 16 extending therethrough and may be turned so that the said passage is brought into alignment with ports 17, 18 in the bushing so as to provide free passage of water from the inlet pipe to the outlet end 10' of the spout. Above the plug 15 the spout is bored for the reception of a stem 22 and the upper end of this stem has a squared end 23 for the reception of an operating knob 24 which is secured on the stem by a screw 25. The knob 24 is provided with a pointer 26 bearing the legend "Shower" and adapted to register with an indicator or arrowhead 27 molded or formed on the upper part of the spout. Depending from the under side of the knob 24 is a projection 28 adapted to engage with one or other of two upwardly projecting stops 29, 30 formed on the spout, and the pointer 26, when in the position shown in full lines at Fig. 2, is in the "Shower" position and the plug 15 prevents the passage of water from the port 18 to the port 17 and, when the pointer 26 is in the position shown in dot-and-dash lines at Fig. 2, the passage 16 is in alignment with the ports 17 and 18 and water passes freely to the outlet 10' of the spout and no water is then supplied to the shower.

In operation the device may be set in readiness for the supply of water either to the tub or to the shower attachment and may remain in such set position indefinitely.

If so desired the plug 15 and stem 22 may be horizontally disposed in the spout instead of ver-

tically as shown on the drawings and the pointer 26 may be suitably modified.

Although the drawings and the above specifications disclose the best mode in which I have contemplated embodying my invention, I desire to be in no way limited to the details of such enclosure, for—in the further practical application of my invention—many changes in form and construction may be made as circumstances require or experience suggests without departing from the spirit of the invention within the scope of the appended claims.

What I claim is:

1. A fitting for the supply of water from a supply pipe to a bathtub and to a shower fitting or attachment, comprising a water spout casing, an inner bushing fitted in the inlet end of the casing, a screw threaded socket in said bushing for the reception of the water supply pipe, aligned ports in the bushing, a tapered plug mounted in said bushing between said ports, a passage in said plug capable of alignment with said ports, a stem extending through the wall of the spout casing and attached to said plug and preventing relative movement of the said casing and bushing, an operating device attached to the outer end of said stem, means for indicating when said stem and plug are in position to prevent the passage of water through the spout, means for limiting the rotary movement of said plug and spring means between the end of the plug and the spout casing to hold the plug tightly in position.

2. A plumbing fitting for the supply of water from a supply pipe, comprising a water spout casing, a bore in the casing for the discharge of water from the spout, an enlarged bore in the inlet portion of the casing, a bushing fitted closely within said enlarged bore, a screw-threaded socket in the end of said bushing for engaging the water supply pipe and for supporting the casing upon said pipe, ports formed in the bushing in alignment with each other and with the first-mentioned bore, a rotary tapered plug valve mounted between said ports with its axis at right angles to the axis of said bushing, a water passage in said plug capable of alignment with said ports, and a stem attached to said plug and extending through the wall of said casing.

3. A plumbing fitting for the supply of water from a supply pipe, comprising a casing for a water spout, a bore in said casing for the delivery of water from the spout, an enlarged bore in the inlet portion of the casing, a bushing fitted tightly within said enlarged bore, a collar on one end of said bushing for screw-threaded engagement with the water inlet end of said spout, a screw-threaded socket in one end of said bushing for engaging the water supply pipe and for supporting the casing upon said pipe, ports formed in the bushing in alignment with each other and with the first-mentioned bore and with the water supply pipe, a rotary tapered plug mounted between said ports with its axis at right angles to the axis of said bushing, a water passage in said plug capable of alignment with said ports, a stem attached to said plug and extending

through the wall of said casing and serving to prevent relative movement of said bushing with respect to said casing, an operating device attached to the outer end of said stem, and means for indicating when said stem and plug are in position to prevent the passage of water through the spout.

4. A fitting for the supply of water from a supply pipe to a bathtub and to a shower fitting or attachment, comprising a bathtub spout casing, a bore in the casing for the discharge of water to the bathtub, an enlarged bore in the inlet portion of the casing, a cylindrical bushing fitted tightly within said enlarged bore, a screw-threaded socket in the end of said bushing for engaging the water supply pipe and for supporting the casing upon said pipe, ports formed in the bushing in alignment with each other and with the first-mentioned bore, a rotary tapered plug valve mounted between said ports with its axis at right angles to the axis of said bushing, a water passage in said plug capable of alignment with said ports, and an actuating stem attached to said plug and extending through the wall of said casing to prevent movement of said bushing within said casing.

5. A fitting for the supply of water from a supply pipe alternatively to a bathtub or to a shower fitting or attachment, comprising a casing for the bathtub spout, a bore in said casing for the delivery of water to the bathtub, an enlarged bore in the inlet portion of the casing, a cylindrical bushing fitted tightly within said enlarged bore, an enlarged end part on one end of said bushing for screw-threaded engagement with the water inlet end of said spout, a screw-threaded socket in the end of said bushing for engaging the water supply pipe and for supporting the casing upon said pipe, ports formed in the bushing in alignment with each other and with the first-mentioned bore and with the water supply pipe, a tapered plug mounted between said ports with its axis at right angles to the axis of said bushing, a water passage in said plug capable of alignment with said ports, a stem attached to said plug and extending through the wall of said casing to prevent movement of the said bushing within said enlarged bore, an operating device attached to the outer end of said stem, means for indicating when said stem and plug are in position to prevent the passage of water through the spout, and a spring in compression between the spout casing and the end of the plug to hold the plug tightly in position in the bushing.
